(57) **CLAIM**

The ornamental design for a modular sofa as shown and described.

DESCRIPTION

FIG. 1 is a perspective view of a modular sofa showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the modular sofa, shown in an open configuration;

FIG. 10 is another perspective view of the modular sofa, shown in an open configuration;

FIG. 11 is a perspective view of the modular sofa where the modular sofa is in a combined state;

FIG. 12 is a perspective view of the modular sofa where the modular sofa is in another combined state; and,

FIG. 13 is a perspective view of the modular sofa where the modular sofa is in another combined state.

The dash-dash broken lines in the drawings depict portions of the modular sofa that form no part of the claimed design.

1 Claim, 13 Drawing Sheets
